(57) **CLAIM**

The ornamental design for an auxiliary faucet, as shown and described.

DESCRIPTION

FIG. 1 is a top, right, front perspective view of an auxiliary faucet;

FIG. 2 is a right side view thereof;

FIG. 3 is a left side view thereof;

FIG. 4 is a front view thereof;

FIG. 5 is a rear view thereof;

FIG. 6 is a top plan view thereof; and

FIG. 7 is a bottom plan view thereof.

FIG. 8A is a top, right, front perspective view of an alternative embodiment of the auxiliary faucet;

FIG. 8B is an enlarged view of a portion of FIG. 8A;

FIG. 9A is a right side view thereof;

FIG. 9B is an enlarged view of a portion of FIG. 9A;

FIG. 10 is a left side view thereof;

FIG. 11 is a front view thereof;

FIG. 12 is a rear view thereof;

FIG. 13A is a top plan view thereof;

FIG. 13B is an enlarged view of a portion of FIG. 13A; and, FIG. 14 is a bottom plan view thereof.

FIGS. 1-5, 7-8A, 9A, 10-12 and 14 show portions of the auxiliary faucet in broken lines.

The broken line portions are shown for environmental purposes and form no part of the claimed design. The broken line segments immediately adjacent the solid line portions of the design define the boundary of the design, but do not themselves form part of the claimed design.
